COMBINED CAKEHOLDER AND COVER
THEREFOR OR SIMILAR ARTICLE

Earl S. Tupper, Upton, Mass.

Application December 23, 1952, Serial No. 22,826

Term of patent 14 years

(Cl. D44—1)

To all whom it may concern:

Be it known that I, Earl S. Tupper, a citizen of the United States and a resident of Upton, county of Worcester, and State of Massachusetts, have invented a new, original, and ornamental Design for a Combined Cakeholder and Cover Therefor or Similar Article, of which the following is a specification, reference being had to the accompanying drawing, forming a part thereof.

In the drawing:

Figure 1 is a perspective view of a combined cakeholder and cover therefor, showing my new design as seen in an inverted position;

Fig. 2 is a perspective view thereof as seen in an upright position; and

Fig. 3 is a sectional view of Fig. 2 taken along the plane 3—3 thereof.

I claim:

The ornamental design for a combined cakeholder and cover therefor or similar article, as shown.

EARL S. TUPPER.
